(57) **CLAIM**

The ornamental design for a bar handle apparatus as shown and described.

DESCRIPTION

FIG. 1 is a top front perspective view of a bar handle apparatus showing my new design.

FIG. 2 is a front elevation view of the bar handle apparatus of FIG. 1.

FIG. 3 is a rear elevation view of the bar handle apparatus of FIG. 1.

FIG. 4 is a top plan view of the bar handle apparatus of FIG. 1.

FIG. 5 is a bottom plan view of the bar handle apparatus of FIG. 1.

FIG. 6 is a left side elevation view of the bar handle apparatus of FIG. 1.

FIG. 7 is a right side elevation view of the bar handle apparatus of FIG. 1; and,

FIG. 8 is a top front perspective view of the bar handle apparatus of FIG. 1, shown in an alternate state with environment.

The dash-dash broken line showing of a bar handle apparatus is for the purpose of illustrating portions of the article and forms no part of the claimed design. The dot-dash broken line in FIGS. 1, 2, and 8 define the bounds of the claimed design and form no part thereof. The dash-dash broken line showing of a weed trimmer is for the purpose of illustrating environmental structure and forms no part of the claimed design.
